UNITED STATES PATENT OFFICE

1,990,986

LUBRICATING APPARATUS

Alexander P. Fox, St. Louis, Mo., assignor to Lincoln Engineering Company, St. Louis, Mo., a corporation of Missouri

Application August 6, 1932, Serial No. 627,719.

6 Claims. (Cl. 184—7)

This invention relates to lubricating apparatus, and with regard to certain more specific features, to lubricating apparatus operable to distribute alternately to two or more pipes, under pressure, quantities of lubricants or the like, such as grease.

The invention is an improvement upon the pressure alternating means described in Patent 1,805,303, issued to Frank S. Barks, dated May 10, 1931.

Among the several objects of the invention may be noted the provision of apparatus of the class described which is self-actuating to effect complete cycles of operation and then to stop 15 until otherwise energized; apparatus which is easily and readily regulable to supply grease at the various outlets, alternately, and at various pressures; apparatus of the class described which embodies means for filtering or freeing the 20 lubricant of undesirable foreign material; apparatus of the class described which provides means for feeding back, or relieving, excess pressure in grease lines beyond itself; and the provision of apparatus of the class described which 25 is relatively simple in construction and operation. Other objects will be in part obvious and in part pointed out hereinafter.

The invention accordingly comprises the elements and combinations of elements, features of 30 construction, and arrangements of parts which will be exemplified in the structures hereinafter described, and the scope of the application of which will be indicated in the following claims.

In the accompanying drawings, in which is 35 illustrated one of various possible embodiments of the invention,

Fig. 1 is a top plan view of a device embodying the present invention;

Fig. 2 is a front elevation of the device of 40 Fig. 1;

Fig. 3 is a vertical cross section taken substantially on line 3—3 of Fig. 1;

Fig. 4 is a vertical cross section taken substantially on line 4—4 of Fig. 1;

Fig. 5 is a horizontal cross section taken substantially on line 5—5 of Fig. 2;

Fig. 6 is a working diagram of parts required for an understanding of the invention; and,

Fig. 7 is another working diagram showing various elements separated for clarity, minor elements being omitted for like reasons.

Similar reference characters indicate corresponding parts throughout the several views of the drawings.

In said Frank S. Barks' Patent No. 1,805,303,

dated May 12, 1931, is shown a lubricant distributing system, comprising, generally, a source of lubricant under pressure, a pair of lubricant delivery lines, and alternator means interposed between the source and the delivery lines alternately delivering the lubricant to each of said lines. The alternator means of said patent are shown particularly in Figs. 5 to 7 and 11 to 14. While such alternator means are satisfactory in operation, they require several individually operating mechanisms. The present invention supplies an alternator having the same general functions as the alternating means of said patent, but having added functions and being simplified in both construction and operation, and being more reliable.

Broadly, the present device comprises an inlet line 23 delivering grease to the inlet connector 7 of an alternator as a whole, there being within the alternator a directing valve 75 which directs fluid into one or the other of the outlet lines 9 and 11. These lines 9 and 11 correspond to similar lines in said Patent 1,805,303. From these lines the grease is measured out in predetermined quantities by suitable measuring distributing valves shown in said Patent 1,805,303.

Each line 9 and 11 is provided with a pressure regulating resistance valve 5 operated by fluid from the respective line 9 or 11. The regulating means permits the pressure in its respective line to build up to a predetermined maximum, and the fluid which operates the regulating means is shunted from the line under pressure to operate said directing means 75 to redirect fluid into the other line. The line which is not in communication with the inlet 7 is exhausted to the supply by directing means 75, whereby the back pressure of fluid in that line is relieved. Also, means is provided whereby the fluid used for operating the directing means is relieved of pressure and redelivered to the supply after it has ceased its function of shifting the directing means.

The part of the circuit connected with the above outlined device is shown in Figs. 6 and 7 wherein said inlet line 23 is shown as being maintained under pressure by a pump P actuated by an electric motor M through a suitable speed reducer S and withdrawing from a supply Y. The motor circuit is adapted to be opened by a pressure-responsive switch W under predetermined conditions of pressure in a line 19, the details of which will be described. Primary starting apparatus in the circuit is not shown as it is not necessary to a complete disclosure of 55

the present invention, the same being reserved for another disclosure.

The maximum pressure which may be attained in either of the lines 9 or 11 is regulable at the 5 pressure regulating devices 5.

The separate engine for performing the function of alternating, shown in said patent, is eliminated herein.

With the above broad description in mind, the 10 details of the apparatus will be set forth.

Referring to the drawings, numeral 1 (Figs. 1, 2 and 7) indicates a rectangular block or body, made preferably of a steel suitable to safely withstand the pressures herein employed. Projecting from the top of block 1 are, first, a filter cap 3, and, second, a pair of adjusting columns 5. On the back face of block 1 a lubricant inlet connection 7 is provided. From the front face of block 1 project a pair of lubricant outlets 9 and 11. 15 On each side face of block 1 is a plug 13, while the right side face of the block has an exhaust line 15 leading therefrom. From the bottom of block 1 project, first, a pair of locking caps 17 corresponding in position to the adjusting columns 5; second, a line 19 leading to said pressure-electric switch W; and, third, a delivery line 21 leading to a suitable pressure gauge (not shown).

Referring now more particularly to Figs. 3, 4, 5 and 7, the lubricant inlet connection 7 will be 30 seen to comprise a pipe 23, which conducts lubricant from the pump or other pressure supplying means. The pipe 23 is threaded at its end into a saddle member 25, which completely encloses and embraces a T-shaped member 27. The member 27 is provided with a longitudinal bore 29 and a cross bore 31, and is threaded at its end 33 to a suitable opening in the body 1. Gaskets 35 seal the joint between the saddle member 25, the T member 27, and the body 1. The arrangement is such that the pipe 23 and saddle 25 may 40 swivel to position on the member 27 before tightening.

Extending from the inlet connection 7 in the body 1 is a bore 37, which is restricted in diameter as at numeral 39. The bore 39 conducts lubricant to a vertical bore 41 in the block 1.

The filter means indicated broadly by numeral 3 comprises a cap 43 threaded into a suitable hole 45 in the body or block 1. A gasket 47 seals 50 the cap 43 and the block 1. The cap 43 is hollow on the inside, being provided with a central bore 49 and an enlarged counterbore 51. In the bores 49 and 51 is fitted a filter member 53. The filter member 53 is generally cylindrical in shape, and 55 has a central bore 55 which connects with the bore 41 hereinbefore referred to. From the central bore 55, radial outlets 57 lead to the counterbore 51. The lower portion of the filter member 53 is provided with a series of projecting 60 rings or flanges 59, which rings 59 are slightly smaller in diameter than the inner diameter of the bore 51, thus leaving narrow annular spaces 61 between said rings 59 and the walls of the cap 43.

65 A counterbore 63 in the block 1 forms an extension of the bore 51 in the cap 3. Leading from the front lower edge of the bore 63 is a passage or bore 65. The bore 65 connects the filter arrangement with a cross bore 67, extending the 70 entire width of the block 1. The bore 67 is illustrated more completely in Fig. 5. Each end of the bore 67 is provided with a counterbored portion 69, which is threaded to receive plugs 13. Each plug 13 is provided with an extending stop 75 portion 71 having a notch 73 therein.

Sliding in bore 67, with a relatively close fit, is a piston valve member 75. The piston member 75 is of generally cylindrical shape, but has peripheral notches 77, 79, and 81 therein. The notches 77 and 81 are of substantially the same width, and relatively narrower than the notch 79. The bore 65, which does not show in Fig. 5, enters the top half of bore 67 at substantially the middle of the block, and is so positioned as always to be juxtaposed to the notch 79.

Still referring to Fig. 5, it will be seen that bores or passages 83, 85, 87 and 89 extend forwardly from the cross bore 67 to the outlets 9 and 11. The bores 83 and 85 terminate in a single bore 91 which is threaded to receive a connecting nipple 15 92. The outlet pipe 9 is similarly threaded in nipple 92. A gasket 96 seals the nipple 92 to the block 1. A similar arrangement is provided for the passages 87 and 89, to connect them with the outlet pipe 11.

Also communicating with the bores 91 are vertical bores or passages 93, each of which in turn connects with a horizontal bore 95. The bores 95 extend inwardly from the opposite sides of the block 1, and are closed at their ends by 20 suitable plugs 98.

Referring now more particularly to Fig. 3, it will be seen that each bore 95 intersects, a bore 97 on the under side of the block 1. The bores 97 are threaded to receive plugs 99, which are 30 locked in position by the outer caps 17. Gaskets 101 seal the caps 17 to the block 1. Extending upwardly from the bore 97 is a bore 103 of smaller diameter. The bore 103 connects the bore 97 with a series of counterbores 105 and 107 made 35 from the top of the block 1, of increasing diameter. The top counterbore 107 is threaded to receive a plug 109. The plug 109 in turn has an upper counterbore 111 threaded to receive the lower end of an adjusting column 113. The column 113 is hollow, and threaded at its upper end to receive a plug 115. The assembly 109, 113, and 40 115 constitutes the exterior portion of the adjusting columns 5 hereinbefore referred to.

Extending slidably through a bore 117 in a 45 plug 115, and a central bore 119 in the plug 109, is a vertical pin 121. The pin 121 extends at 123 from the column. At the lower end of the hollow column 5, the pin 121 is provided with an annular shoulder 125. A compression spring 127 is 50 mounted within the hollow column 113, and reacts at one end upon the shoulder 125, and at the other end upon the upper face of the plug 115.

Below the shoulder 125, the pin 121 is reduced in diameter, to pass through the central bore 119 55 of the plug 109. Below the plug 109, it is provided with an annular recess indicated at numeral 128. It is also reduced in diameter at its lower end 129. Said lower end 129 carries thereon a valve closure element 131 of relatively small projected pressure area. The valve closure element 131, as will be seen in Fig. 5, is exteriorly 60 square or otherwise polygonal, but of such size that the corners of the square slidably engage the walls of bore 103. The section shown in Fig. 3 is a section through the closure member 131 on a flat side. This construction provides chordal openings 133 between the closure member 131 and the walls of bore 103. The lower end 65 of the closure member 131 is provided with a conical projection 137, which constitutes the valve closing means per se having said relatively small projected area.

The conical portion 137 seats against a central opening 135 drilled into the plug 99. A gasket 75

139 seals the upper end of plug 99. A number of radial openings 141 are provided in the plug 99, said radial openings 141 connecting the central bore 135 to the counterbore 97, and thence 5 to the lubricant inlet passage 95.

In the upper counterbores 105 and 107 is mounted a generally cylindrical element 143 which is an extension of the member 109. The element 143 is provided with a suitable central 10 opening 145 to pass the pin 119. The lower portion of the element 143 is of considerably less diameter than the counterbore 105, and hence leaves an annular space 147 therearound. Vertically spaced bores 149 and 151 connect the central bore 145 to the annular space 147. Radial passages 153 at the upper end of the element 143 similarly connect the bore 145 to the annular space provided in the upper counterbore 107.

In normal assembly of the device, a slight space 20 is left between the lower edge of the element 143 and the shoulder of the counterbore 105, as indicated at numeral 155. The space 155 is secured by the engagement of the upper portion of the element 143 with a shoulder 157 formed by a 25 short counterbore in the counterbore 107.

A diagonal bore 159 connects the lower portion of the counterbore 105 with the central longitudinal bore 67. Another diagonal bore or passage 161 connects the lower edge of the counterbore 107 to a horizontal bore 163 (Fig. 5), and a continuing diagonal bore 165. The horizontal bore 163 is drilled inwardly from the side of the block 1, and is provided at its inner end with a conical portion 167, upon which a ball 169 seats. 30 A bore 171 of restricted diameter continues the bore or passage 163 to the point where it engages a vertical bore 173. The vertical bore 173 is drilled upwardly from the bottom of the block, and suitably threaded at its lower end to receive 40 the pipe 19, by which it is connected to a suitable pressure-operated switch for closing off the source of pressure of the lubricant at the inlet 7. Also connected to the vertical bore 173 is a continuation 175 of the bore 83 (Fig. 5).

The outer end of horizontal bore 163 is closed 45 by a plug 177, which has an inwardly extending pin 179 acting as a stop member to prevent the ball 169 from unseating to a too great extent (Fig. 5). The ball 169 automatically reseats under back pressure on the downstream side, but it is to be understood that a spring reseating means 50 may also be employed, if desired. In Fig. 7 the pin 179 is simplified for diagrammatic purposes.

The arrangement of the elements in the bore 55 163 as thus described is desirably provided only on one side of the block. As shown in Fig. 5, it will be seen that at the other side of the block the corresponding bore 164 contains no ball or ball seat, but comprises a simple bore closed by 60 a plug 181.

The respective slanting bores 165, for the two sides of the device, connect with horizontal bores or passages 183 (Figs. 3 and 5) drilled in from the back of the block 1. Concentric with the 65 bores 183 are enlarged counterbores 185 suitably threaded to receive plugs 187. Seating on the shoulder between the bore 183 and counterbore 185 is a disc 189, which is held in position by a compression spring 191 in turn held in a counterbore 193 in the plug 187. The discs 189, and assembly therewith, constitute check valves.

A horizontal bore 195 (Fig. 5) connects the two counterbores 185, and continues to the right-hand side of the block 1, where it is threaded to 70 receive pipe 15. Pipe 15 is a lubricant exhaust

pipe, and preferably leads back to the store of lubricant from whence the lubricant may be pumped to reenter the system at the inlet 7.

Referring again to Fig. 4, it will be seen that a vertical bore or passage 197 is provided which 5 communicates with the central part of the main bore 67, and into the lower end of which is threaded the pipe 21, which pipe 21 leads to the suitable pressure gauge (not shown).

Threaded bores 199 (Figs. 4 and 5) are provided in the block 1 for receiving suitable mounting studs.

The device operates in detail as follows:

Lubricant, such as grease, or like material, enters under considerable pressure through the 15 inlet 7 (Fig. 3), the motor M and pump P building up this pressure while they are running. The grease under pressure passes through bores 37, 39, and 41, and into the filter 3. Rising in the central bore 55, it is forced outwardly through 20 the openings 57 into the annular region 51 (Fig. 4). Under the pressure of the grease behind, it is now forced downwardly past the flanges 59, through the relatively narrow peripheral passages 61. The passages 61 are too narrow to permit any foreign matter, such as flakes of rust or the like, to follow the grease. From time to time the cap 43 and element 53 may be removed from the block 1 to clean away the accumulated foreign matter. Next, the filtered grease reaches 30 the annular region 63 (see also Fig. 7). In Fig. 7 the dark stippling indicates high pressure grease, whereas light stippling indicates grease under a lower pressure.

From the region 63, the grease passes through 35 passage 65 to the central, main bore 67 (Fig. 5). Depending now upon the position of the piston element 75 (see Fig. 5), which determines the position of groove 79, the grease passes, by way of said groove 79, to either the passage 85 or 40 the passage 87. For the present, the grease will be considered as passing, in the arrangement shown in Fig. 5, to the passage 87. The passage 87 conducts the grease to outlet pipe 11. It will be assumed that the pipe 11, and devices subsequent thereto, are already filled with grease, so that pressure is promptly built up in line 11. This pressure forces some of the grease out through the respective passage 93, from whence 45 it is forced through the respective passage 95 to the space provided by counterbore 97. Here it is stopped by the valve element 131. The pressure of grease builds up until it is great enough to unseat the valve element 131 against spring 127, which has been set at a predetermined pressure 50 by manipulation of plug 115. Unseating of the valve element 131 moves pin 121, and hence gives a visible signal at the exterior of the device when the alternation takes place.

Having unseated valve element 131, the grease 55 passes into bore 103. After unseating, the area pressed against by the grease is increased. Hence with the small projected area at 137 when the valve 131 is closed, a relatively small spring 127 may be adapted to maintain closure against 60 high pressures but after opening, the increased area presented ensures maintenance of opening. With the upward movement of the pin 121, its lowermost, narrowest portion 129 is moved so that a passage is provided therearound from bore 65 103, through bore 149, to annular region 147. The opening 151 has meanwhile been shut off by the less narrow portion of pin 121 in bore 119.

From the annular space 147 the grease is now 70 compressed through bore 159 into central, main 75

bore 67, but in this case at the end of said bore (see Fig. 5) in the region of the counterbore 69. As the grease fills the counterbore 69, it exerts a pressure upon the end of piston element 75, 5 and ultimately drives said piston (to the left, Fig. 5) to the other end of the bore 67, the piston element thus assuming the position shown in Fig. 7. This change of position of the piston 75 changes the notch 79 to the extent that lubricant is now directed into line 85 and pipe 9, instead of into line 87 and pipe 11.

The pressure in line 9 is communicated to the respective opening 93 and from thence to the respective valve 131 to lift the same and to 15 cause delivery of a charge to the opposite end of the piston valve 75, thus returning the same to the position shown in Fig. 5. The return causes the groove 77 to be aligned with the passage 83 so that pressure is relieved in the pipe 9 through 20 the check valves 169 and 189 to the return pipe 15. At the same time the surge engendered as this high pressure is relieved is not instantaneously dissipated, because of friction in the lines and the resistance of check valves 169 and 183 25 at the left in Fig. 5. Hence an instantaneous pressure occurs in the branch line 173 which leads to the switch W by way of line 19. This causes opening of the switch and cutting out of the motor M with consequent stoppage of the 30 pump P. It will thus be seen that the apparatus has made a complete cycle of operation and then is automatically cut out of operation by its own functions.

The surge above referred to is dissipated 35 through the check valves 169 and 183 shortly after occurring. This causes a reclosing of the switch W but by this time independently controlled apparatus in the line L causes an opening of the circuit at another point. Thus, al- 40 though the switch W is closed to potentially restart the motor M, the circuit L is open. Restarting is effected by said other means in the line and is not described herein because it does not form a part of the invention herein claimed.

45 When alternation takes place, the supply of high pressure grease is at once cut off from the respective passages 93 and 95, and counterbore region 97. Thus the valve 131, under the influence of spring 127, at once seats. With seat- 50 ing of the valve, pin 121 moves downwardly, blocking off bore 149 but opening bore 151 (the position as shown in Fig. 3). Thus, grease in the counterbore 69 (Fig. 5) can flow back through passage 159, annular space 147, bore 151, notch 128, and passages 153 into the annular space 55 provided by counterbore 107, and thence through bore 161, bore 163, bore 165, check valve 189, and bore 195 to exhaust pipe 15, thus relieving the pressure. Grease trapped in bore 103 passes 60 through annular space 155 into annular space 147, and thence to the exhaust pipe 15 in the manner described. The annular space 155 is narrow enough to permit slow exhausting of grease in the manner described, but too narrow 65 to pass enough grease to interfere with the positive movement of the piston element 75. If the annular space 155 were not provided, pressure might be trapped in the space 103 so as to reduce the effectiveness of spring 127 in closing the 70 valve 131.

In order to prevent the piston 75 (Fig. 5) from at any time being held on "dead center" (such that grease is supplied to neither passage 85 nor passage 87), the notch 79 is preferably made a 75 little longer than the distance between the clos-

est edges of passages 85 and 87, so that it is, at all times, necessarily in communication with one of said passages.

It will be noted that the passages 165 and 164 are checked against flow from horizontal bore 195 by check valve discs 189. These check valves prevent the surge engendered by the release of high pressures in the respective lines 9 and 11 from being improperly delivered to the end of the valve stem 75. They prevent the 10 valve stem 75 from being balanced after partial movement by pressure at each end created by surge when relieving the respective lines 9 or 11 of pressure.

Thus these respective check valves each protect one end of the valve stem from being subjected to the surge or exhaust pressure while the other end is being acted on by pressure shunted from the lines 9 or 11 under pressure.

As to the check valve 169, it will be noted that 20 it has no counterpart in the passage 164, because the passage 164 does not communicate with any line such as 19. As will be remembered, the line 19 communicates back pressure to the pressure switch which controls the operation of a compressor for delivering grease to the inlet line 23. The check valve 169 prevents pressure of trapped grease which is exhausting from behind the valve stem 75 on the left-hand side of the Fig. 5 from reaching passage jets 173 and 19, said returning grease being delivered through the left-hand check valve 189 to the line 15.

While the device has been herein described in connection with the handling of lubricants, particularly grease, it will be apparent that other fluids might also be handled without departing from the field of the invention.

In view of the above, it will be seen that the several objects of the invention are achieved and 40 other advantageous results attained.

As many changes could be made in carrying out the above constructions without departing from the scope of the invention, it is intended 45 that all matter contained in the above description or shown in the accompanying drawings shall be interpreted as illustrative and not in a limiting sense.

I claim:

1. In apparatus of the class described, a pressure switch, a body having an inlet, compression means for supplying fluid to the inlet, said body also having a plurality of outlets as well as a plurality of exhausts and a pressure switch connection, the pressure switch when operated causing 50 said compression means to discontinue supplying fluid to the inlet, a movable distributing valve in said body adapted in alternate positions to connect the inlet with one outlet while independently connecting the other outlet to one of said exhausts thereby to effect inlet and exhaust positions for opposite ends thereof, resistance valves associated with said outlets adapted to assume open and closed positions, means connecting said outlets with opposed areas on the distributing valve 55 whereby movement of the distributing valve is effected under outlet pressure when the respective resistance valves are open, means connecting said distributing valve areas to the respective exhausts when said resistance valves are closed, check valves in the respective exhausts, a check valve connection opening from said switch connection to one of said exhausts, and a port on said distributing valve adapted in one position of 60 said distributing valve to connect one of said 65 exhausts.

outlets with the pressure switch connection when said distributing valve is in exhaust position to connect the last-named outlet to the last-named exhaust, there being a surge in pressure in the 5 pressure switch upon said connection, the surge in pressure operating the pressure switch.

2. In apparatus of the class described, a pressure switch, a body having an inlet, compression means for supplying fluid to the inlet, said body 10 also having a plurality of outlets as well as a plurality of exhausts and a pressure switch connection, the pressure switch when operated causing said compression means to discontinue supplying fluid to the inlet, a movable distributing valve in said body adapted in alternate positions to connect the inlet with one outlet while independently connecting the other outlet to one of said exhausts thereby to effect inlet and exhaust positions for opposite ends thereof, resistance 15 valves associated with said outlets adapted to assume open and closed positions, means connecting said outlets with opposed areas on the distributing valve whereby movement of the distributing valve is effected under outlet pressure 20 when the respective resistance valves are open, means connecting said distributing valve areas to the respective exhausts when said resistance valves are closed, a throttle connection opening from said switch connection to one of said exhausts, and a port on said distributing valve adapted in one position of said distributing valve to connect one of said outlets with the pressure switch connection when said distributing valve 25 is in exhaust position to connect the last-named outlet to the last-named exhaust, there being a surge in pressure in the pressure switch upon said connection, the surge in pressure operating said switch.

3. In apparatus of the class described, a body 30 having an inlet, compression means for supplying fluid to the inlet, said body also having a plurality of outlets as well as a plurality of respective exhausts and a pressure switch connection, a pressure switch when operated causing said

compression means to discontinue supplying fluid to the inlet, a movable distributing valve in said body adapted in alternate positions to alternately connect the inlet with the respective outlets while independently connecting the other respective outlets with respective exhausts thereby to effect inlet and exhaust positions for opposite ends thereof, resistance valves associated with said outlets adapted to assume closed positions against certain outlet pressures and open positions against greater outlet pressures, means connecting said respective outlets with opposed areas on the distributing valve whereby movement of the distributing valve is effected to close the outlet receiving pressure when the respective resistance valve is open, means connecting said distributing valve areas to the respective exhausts when said resistance valves are closed, a check valve connection opening from said switch connection to one of said exhausts, and a port on said distributing valve adapted in one position of said distributing valve to connect one of said outlets with the pressure switch connection when said distributing valve is in exhaust position to connect the last-named outlet to the last-named exhaust, there being a surge in pressure in the pressure switch upon said connection, the surge in pressure operating said switch.

4. Apparatus made in accordance with claim 3 and including regulating means for said resistance valves adapted to determine the outlet pressures at which the respective valves shall open.

5. Apparatus made in accordance with claim 3 and including means for independently regulating the resistance of said resistance valves, to control the respective pressures in the respective outlets at which said respective resistance valves shall open.

6. Apparatus made in accordance with claim 3 and including at least one regulating means for determining the pressure at which at least one of said resistance valves shall open.

ALEXANDER P. FOX.
